UNITED STATES PATENT OFFICE

CHARLES T. BRENNAN, OF WATERBURY, CONNECTICUT

OPEN-DIE-HEADING MACHINE

Application filed June 29, 1928. Serial No. 289,236.

In an open die heading machine, such for instance as illustrated in the Campbell Patent No. 926,170, dated June 29, 1909, the stock is fed into opened dies which are then closed and moved transversely to shear off a piece 5 of the stock and carry the cut piece into line with the punches. Toggle mechanism is arranged to effect the closing of the dies and their transfer, and this mechanism has to be accurately adjusted in order that the dies 10 shall properly pinch, correctly transfer and securely hold the stock. This invention relates to the means which are employed for setting the toggle mechanism so that the dies 15 will grip and hold the stock in the most effective manner.

The object of the invention is to provide simple means whereby the mechanism may be adjusted to effect any desired variation 20 of pressure of the dies along the length of the stock, and then adjusted to ensure the required pinch of the dies on the stock and transfer of the stock into line with the punches, the latter adjustment being made 25 without disturbing the former adjustment.

In the mechanism illustrated as embodying this invention there are two independent but simultaneously operated toggles, the forces of which are coincidentally transmitted 30 to the dies for closing and transferring them. The toggle backing blocks are independent of each other and abut against two opposing angular faces on a backing plate, which angular faces are so related that a longitudinal 35 movement of the backing plate transversely of the toggles will cause a slight advance of one toggle block and permit a slight retraction of the other toggle block, the advance of one and the retraction of the other being 40 equal and coincident. By moving this single backing plate with the opposing angles one way or the other the toggles can be adjusted to so transmit their pressures to the dies that either end of the dies may be caused to pinch 45 the stock more tightly than the other end.

Between the backing plate and the frame is a backing wedge that, after the backing plate has been adjusted to determine the relative pressures of the toggles on the dies, is adjusted to give the required pinch of the dies 50 on the stock, and so locate the toggle backing blocks that the toggles will accurately transfer the dies and stock, and this backing wedge is capable of adjustment without altering the adjustment of the backing plate with 55 relation to the toggles.

In the accompanying drawings Fig. 1 shows a plan view with part of the frame cut in horizontal section, of the front end of an open die heading machine provided with a 60 toggle adjusting means arranged according to this invention. Fig. 2 is a vertical section through the frame of the machine taken on approximately the plane indicated by the dotted line 2—2 on Fig. 1. Fig. 3 is a plan of 65 the toggle backing blocks and the backing plate and backing wedges in one relation. Fig. 4 is a similar view of the same with the parts adjusted to a different relation. Fig. 5 shows a modified form of the toggle backing 70 blocks, backing plate and backing wedge for adjusting the toggles.

The dies 1 and 2 are arranged to be moved transversely on a bed plate 3 in front of a back plate 4 in the die pocket 5 formed in the 75 front end of the frame 6, as is usual in machines of this type. At one side of the dies is a filling plate 7 and facing this plate is a cap 8 that is attached to the ends of plungers 9 and 10 which are longitudinally movable 80 in the frame. The other ends of the plungers have socketed heads 11 and 12.

In the frame at one side is a longitudinally movable slide 13, and fitted in an opening in this slide so as to reciprocate therewith but 85 free to move transversely thereof are two independent blocks 14 and 15 which carry the studs 16 and 17 upon which the joined ends of the toggle links 18 and 19 are 90 pivoted. The outer ends of the toggle links 18 and 19 are

hinged in the socketed heads of the plungers and the outer ends of the toggle links 20 and 21 are hinged in the socketed backing blocks 22 and 23. These backing blocks are independently adjustable in the frame but are secured in position, after they have been adjusted, by screws 24 and 25. The rear faces of the toggle backing blocks are oppositely inclined with relation to each other and may be placed side by side either as shown in Fig. 4 or as shown in Fig. 5. Fitting against these inclined faces of the toggle backing blocks are the opposing angular faces of the backing plate 26. This backing plate is capable of movement transversely of the toggles, and screws 27 and 28 are turned through the frame against the ends of the backing plate for the purpose of adjusting it and holding it in position after it has been adjusted.

Between the backing plate and the wall of the frame is a backing wedge 29 that is capable of movement transversely of the toggles. Screws 30 and 31 are turned through the frame against the ends of the backing wedge for adjusting and securing it in adjusted position. Openings are made through the backing plate and backing wedge so that the screws 24 and 25 may be passed through them into the toggle backing blocks without interfering with the adjustments of the plate and wedge.

As the toggles are straightened the plungers and cap move forward and after closing the dies on the stock move the dies with the stock from feed position to punching position which is that in which the dies are illustrated in Figs. 1 and 2. When the toggles are collapsed the plungers and cap are withdrawn and the dies caused to follow back by mechanism well known to those familiar with this art. In operating machines of this type it is customary to have the dies pinch the stock with slightly greater force at the outer ends than at the inner ends and the amount of this pinch may be varied with different kinds of work and different quality of stock.

With the construction illustrated the screws 27 and 28 are first turned to move the backing plate in the required direction to advance one and permit the retraction of the other of the toggle backing blocks to such an extent as will increase or diminish the pressure transmitted by the plungers 9 and 10 on the dies as the toggles are straightened. After this adjustment has been made to give the desired variation of pressure along the length of the dies, the backing wedge is adjusted by turning the screws 30 and 31 to give the required over all pinch of the dies. By adjusting the single backing plate the pressure exercised by either toggle may be quickly altered with relation to the pressure of the other toggle, and the amount of this adjustment is slight as the pushing forward

of one toggle backing block allows the other toggle backing block to retract coincidently and an equal amount. After this adjustment has been made the backing wedge can be adjusted to meet the requirements without disturbing the relative adjustments of the toggles. When the backing plate and backing wedge have been located in the required positions the screws 24 and 25 are tightened so as to hold the toggle backing blocks in place.

The invention claimed is:—

1. In an open die heading machine in combination with the dies, a plurality of toggles for closing and transferring the dies, means engaging toggle members and movable transversely of the toggles for coincidently giving them a relative adjustment, and a backing wedge engaging said means.

2. In an open die heading machine in combination with the dies, a plurality of toggles for closing and transferring the dies, and a single wedge plate engaging toggle members and movable transversely of both the toggles for coincidently giving them a relative adjustment.

3. In an open die heading machine in combination with the dies, a plurality of toggles for closing and transferring the dies, a backing plate with angular faces engaging toggle members and movable transversely of the toggles for giving them an inter-dependent relative adjustment, and a backing wedge engaging said plate.

4. In an open die heading machine in combination with the dies, a plurality of toggles for closing and transferring the dies, a backing plate engaging toggle members and movable transversely of the toggles, said plate having opposed angular faces for imparting an inter-dependent relative adjustment to the toggles, a backing wedge engaging said plate, and screws engaging the ends of said plate and wedge for adjusting them longitudinally of the toggles.

5. In an open die heading machine in combination with the dies, a pair of simultaneously actuated independent toggles for opening and closing the dies, and a one-piece backing plate movable transversely of said toggles, said plate having opposed angular faces engaging independent toggle members whereby the longitudinal movement of said plate will cause one toggle to advance and coincidently permit the other toggle to retract an equal distance.

6. In an open die heading machine in combination with the dies, a pair of simultaneously actuated independent toggles for opening and closing the dies, a one-piece backing plate movable transversely of said toggles, said plate having opposed angular faces engaging independent toggle parts whereby the movement of said plate will cause one toggle to advance and coincidently permit the other

toggle to retract an equal distance, and screws engaging the ends of said plate for adjusting it transversely of the toggles.

7. In an open die heading machine in combination with the dies, a plurality of toggles for closing and transferring the dies, a single plate with reverse angular faces engaging the toggle members and movable transversely of the toggles whereby the toggles may be relatively adjusted, and a backing wedge engaging said plate, whereby the toggles may be adjusted simultaneously.
